WELL DEPTH RECORDING

John T. Hayward, Tulsa, Okla.

Application December 30, 1939, Serial No. 311,805

16 Claims. (Cl. 33—134)

This invention relates to a chart drive and particularly to a drive mechanism for driving a depth recording chart from the movements of drilling tools in a well.

In the development of modern well drilling methods, particularly rotary drilling, wherein a drilling fluid, such as mud fluid, is circulated through the well during drilling, the character of the strata through which the drill progresses are difficult of identification because the cuttings and the native fluids contained therein become obscured in the fluid. Recently new methods have been developed by this inventor, described particularly in his application Serial No. 187,619, filed January 29, 1938, now U. S. Patent No. 2,214,674, Sept. 10, 1940, whereby the character of the traversed strata may be readily determined directly from the mud stream during drilling and the various strata logged at their respective depths. In these methods, as well as in connection with other operations about a drilling well, it is highly important that the progress of the drill and depth of the well be known at all times within very narrow limits of accuracy. In logging particularly, it is important that those tests and indications which are representative of particular strata be correctly related to the actual depth of these strata in the well. The present invention, therefore, is directed to a system for driving a chart, such as the usual recorder strip chart, whereby the chart will move in substantially exact synchronism with the progress of the drilling tools in the well, and whereby the various tests and indications representative of the traversed strata can be brought into their proper relationship to depth on the chart. By this system a continuous accurate record of the depth of the well can be made on which curves characteristic of the traversed strata can be traced in proper relationship to the depth.

The system of this invention employs a novel form of drive mechanism whereby only those movements of the drilling tools which represent progressively increasing depth of the well are employed to drive a strip chart carrying footage indications thereon. It will be obvious to those skilled in the art that in the ordinary methods of rotary drilling, the drilling tools make numerous movements in and out of a well which are not directly representative of increasing depth of the well. For example, the drilling string must be frequently withdrawn from and inserted into the well when changing bits, when adding new joints of drill pipe, when removing defective sections of the drill pipe, when reaming down to a previ-

ously attained depth, and for various other operations.

It is a principal object, therefore, of this invention to provide an apparatus whereby only those movements of the drilling tools which are representative of progressively increasing depth are selectively employed to drive a chart bearing the depth record.

Another object is to provide a novel form of selective transmission for the aforesaid movements from the drilling tools to the depth recording chart.

Still another object is to provide a novel form of transmission employing counting devices for selecting those movements of the drilling tools which are transmitted to a depth reading chart.

A further object is to provide in conjunction with the transmission, apparatus of this invention, additional mechanism for mechanically introducing therein correction factors to compensate for wearing of the parts and for changes in length of portions of the drilling tools.

An additional object is to provide a novel form of connection between the drilling tools and the transmission mechanism proper of this invention.

Other objects include the provision of electrically operated controls, actuated by the transmission mechanism for selecting the desired movements to be transmitted to the chart; for providing either audible or visible signals, or both, at certain stages in the operation of the device; to control the operation of the pens which draw the various curves on the chart; and for numerous other operations which are directly related to the progress of the drill in the well.

Various other objects and advantages of my new invention will become apparent to those skilled in the art from the following detailed description when read in conjunction with the accompanying drawings which illustrate a preferred form of this invention and several useful embodiments thereof.

In the drawings:

Fig. 1 is a general assembly showing a drilling rig and the chart drive mechanism connected thereto.

Fig. 2 is a sectional detail taken along line 2—2 of Fig. 1 to better illustrate a novel form of connection between the drill rig and the chart drive mechanism.

Fig. 3 is a detail in perspective of the connection between the drill tools and the chart drive mechanism.

Fig. 4 is an enlarged assembly of the chart drive mechanism proper.

Figs. 5 and 6 are details of the apparatus of Fig. 4.

Fig. 7 is a modified form of one of the parts of the chart drive mechanism.

Fig. 8 is an assembly similar to Fig. 4 but including electrical circuits and connections employed in other modifications of this invention.

Figs. 9 and 11 are details of the apparatus illustrated in Fig. 8.

Fig. 10 is a sectional view taken along line 10—10 of Fig. 9, and

Fig. 12 is a simplified and more or less symbolic representation of a form of selective transmission included in this invention.

Referring to the drawings and to Fig. 1 in particular, a conventional derrick 10 is shown mounted over a well 12. The derrick is equipped with the usual crown block pulley 14 from which is suspended a conventional traveling block 16 by means of cables 18. The drilling string 20, of conventional construction, is suspended from the hook 22 carried by the traveling block. The drilling string includes the usual water swivel 24, to which is attached the ordinary Kelly joint 26 which is in turn connected to the usual jointed hollow drill pipe 28 carrying a drill bit 30 at its lower end. The drilling string extends through the usual rotary table 32 which rotates the drilling string by turning the Kelly joint in the usual way.

Since all vertical movements of the drilling string 20 in well 12 necessarily result in corresponding vertical movements of traveling block 16, and these in turn result in corresponding rotary movement of crown block pulley 14 through the movements of cables 18 about the pulley, the latter provides a convenient take-off connection for transmitting the vertical movements of the traveling block and drilling string to suitable recording apparatus to be later described. A convenient form of take-off connection to pulley 14 is shown in enlarged detail in Figs. 2 and 3 particularly. This connection consists of a measuring wheel 11 mounted on an axle 13 which is suitably journaled in the forks of a yoke 15 which is in turn carried by one end of an arm 17 which has its other end rotatively mounted on shaft 19 which is fixedly attached to the beams 21 forming a part of derrick crown structure. The measuring wheel 11 is arranged to run inside the groove 23 of crown block pulley 14 and the side edges of wheel 11 are held in close frictional contact with the adjacent sides of groove 23 by pressure applied through a coil spring 25 which has one end attached to an intermediate portion of arm 17 and the other to one of the beams 21 at a point beneath arm 17 (see Fig. 3). The peripheral surface of measuring wheel 11 has a groove 27 to permit the wheel to clear cable 18 which is threaded in pulley 14. By mounting measuring wheel 11 to run inside the groove 23 of pulley 14, a very efficient drive connection is provided from pulley 14 to measuring wheel 11, since the sides of groove 23 are ordinarily machined surfaces and are kept smooth by the rubbing action of the steel cable 18. By accurately machining the side edges of wheel 11 a very positive frictional contact can thus be maintained between the pulley and the wheel. Spring 25 provides a yieldable hold-down which permits some relative movement between the contacting members while maintaining positive contact between them.

Since the diameter of pulley 14 is fixed and the number of cables threaded between the pulley

and the traveling block 16 are known, although only a single loop is shown, then by simple calculation, the relationship of the vertical movement in feet, of the traveling block 16 and, therefore, of the drilling string to the rotations of the pulley 14 can be easily determined. By properly proportioning measuring wheel 11 in relationship to the diameter of pulley 14, one turn of wheel 11 can be made to measure any desired length of vertical movement of the drilling string. A convenient proportion is one wherein each turn of measuring wheel 11 represents one foot of vertical movement of the drilling tools.

It will be understood that numerous other measuring devices may be used in place of that described. Another form which may be used is described in detail in my U. S. Patent No. 2,166,212, dated July 18, 1939.

Axle 13 of the measuring wheel 11 is connected by a flexible shaft 29, of conventional construction, to the armature of the drive motor 31 of a self-synchronous transmission system, the function of which is well known in the electrical art and is commonly referred to as a "Selsyn" system. Thus each turn of wheel 11 produces one rotation of the armature of driver motor 31 which in turn synchronously transmits this rotation electrically through leads 33 to the armature of the driven motor 35 of the Selsyn system, which correspondingly rotates the armature shaft 36 on which is mounted a conical smooth surfaced drive pulley 38. By the aforescribed arrangement of apparatus, it will be seen that means has been provided whereby all the vertical movements, in either direction, of traveling block 16, and of the drilling string 20 when suspended therefrom, are translated into rotations in the corresponding direction of shaft 36 and pulley 38, each rotation of which will represent one foot of vertical movement of the traveling block or of the drilling string where measuring wheel 11 has been so proportioned that each turn of this wheel corresponds to one foot of vertical movement of the drilling string. Also, the rotations of shaft 36 and pulley 38 are now available for connection to a strip recorder chart 40, of more or less conventional form, by means of a novel form of selective transmission apparatus which forms one of the important features of this invention.

The selective transmission mechanism of this invention includes a main drive shaft 42 which drives in series through an auxiliary differential designated generally by the numeral 44, and a selecting differential, designated generally by the numeral 46, through a shaft 42a, to a pair of driven shafts 48 and 50, respectively. Driven shaft 48 is connected by a sprocket and chain drive 52 to a first countershaft 54 which is connected to a revolution counter 56 of more or less conventional construction. Driven shaft 50 is connected by a sprocket and chain drive 58 to a second countershaft 60 which is connected to a second revolution counter 62. Countershaft 60 extends through the case of counter 62, the extension forming a stub shaft 64, which is connected by gear connections, designated generally by the numeral 66, to a suitable drive for chart 40. Countershaft 60 is provided with a friction brake, designated generally 68, the function of which will be explained in greater detail herein-after. The end of main drive shaft 42 anterior to auxiliary differential 44 carries a smooth cone shaped drive pulley 70, which is positioned adja-

cent to drive pulley 38 but slopes in the opposite direction to the latter. A variable gear 72, of conventional construction, is positioned between the adjacent faces of drive pulleys 38 and 70 and is adapted to be adjustably moved between the faces of these pulleys by means of screw shaft 74 which is suitably journaled and rotatable by means of a handle 76. Variable gear 72, as noted, is of conventional construction and is provided to vary the speed ratios between the drive pulleys 38 and 70 so as to compensate for any variations in rotations of pulley 38 relative to the movements of the drilling string resulting from wear or variation in any of the parts constituting the drive connection from the drilling string to shaft 36 of Selsyn motor 35. This correction mechanism is very useful, as the gear and pulley sizes through the drive connection are preferably designed to transmit one rotation of shaft 36 and pulley 38 for each foot of movement of the drilling string. The selective transmission mechanism to chart 40 is in turn ordinarily designed to carry the rotations from drive pulley 38 in a one-to-one ratio to countershafts 54 and 60 and thence to chart 40 whereby the chart will be caused to move a distance representing one foot of depth of the well for each rotation of countershaft 60. By use of variable gear 72 any errors occurring in the drive connection mechanism due to wearing of the parts can be corrected and compensated for in transmitting the rotations of shaft 36 and pulley 38 to the transmission mechanism, and the chance for error in the chart drive is thereby eliminated.

As noted previously, the crown block pulley 14 engages in numerous rotations during drilling which are responsive to movements of the drilling string other than those which represent increasing depth of the well. For example, when the drilling string is drilling ahead, drilling ordinarily continues for an interval of depth which is substantially equivalent to the length of the Kelly joint 26, which may be as much as thirty or forty feet or more. This movement of the drilling string, since it represents progressive deepening of the well, it is desired to transmit to the recording chart. When, however, this drilling interval is completed, a new section of drill pipe must be added, or it may be desired to remove the entire drilling string from the well, as for example, to change the bit. The resulting reverse movements of the drilling string from the well are, of course, transmitted to the crown block pulley 14 and its rotations are then transmitted to the transmission mechanism connected to the chart. Since, however, these reverse movements do not represent increasing depth of the well, and since it is inadvisable and undesirable to permit corresponding reverse movement of the chart 40, means must be provided for selectively accumulating in the chart drive mechanism only those movements which represent progressive deepening of the well. Such means must, therefore, enable the chart to be held at a position corresponding to the attained depth of the well, while the non-significant movements of the drilling string occur, and then to permit the chart to move ahead again only when the drill bit begins to move downwardly in the well from the previously attained maximum depth. This maximum depth measurement is supplied by means of counter 62 which will be designated as the maximum counter, while the measurements of the "off-bottom" movements of traveling block 16 or of the drilling string are

supplied by means of counter 56 which will be designated as the off-bottom counter. The details of the apparatus and the manner in which it functions will be described hereinafter.

5 Since the essential element of the present invention comprises a novel form of selective transmission mechanism which is of somewhat complex character in the modification illustrated particularly in Figs. 4, 5 and 6, reference will be 10 first had to the more or less simplified design illustrated in Fig. 12 for the purpose of explaining the functioning of such a transmission.

15 Numeral 100 represents a main drive shaft which is rotative first in one direction and then in the other for varying numbers of rotations. Main shaft 100 is drivingly connected through a differential 102 to a first driven shaft 104, which is connected by a gear 106 to the ring gear 108 of the differential, and to a second driven shaft 110 which is connected to one of the mitre gears 112 of the differential and extends through an axial opening in the ring gear 108. The gear ratios are preferably such that each of the shafts 104 and 110 make one rotation for each rotation of main shaft 100. The shafts 104 and 110 are threaded and their ends are journaled in a supporting frame 114. A threaded nut 116 carrying a pointer 117 is mounted on second shaft 110 and held against rotation by a guide bar 118 extending between the end members of frame 114. Thus rotation of shaft 110 causes nut 116 to move back and forth along shaft 110 depending upon the direction of rotation of the latter. A stop member 120 is positioned on the right hand end 20 of guide bar 118 to positively limit the movement of nut 116 in the right hand direction. A second nut 122 carrying a pointer 124 is mounted on shaft 104 and held against rotation by a second guide bar 126, so that it is also adapted to move 25 along shaft 104 when it is rotated. For purposes of explanation, each of the threads will be taken to represent one foot of lineal movement corresponding to one rotation of main shaft 100 and also of the driven shafts 104 and 110. A scale 30 128 bearing indicia representing rotations of shaft 100, or feet, as the case may be, is positioned parallel to shaft 104 and in indicating relationship to pointer 124. Shaft 104 is provided with an outboard extension 130 which is in frictional engagement with a symbolically illustrated friction applying member 132. A second scale 35 134 bearing indicia similar to scale 128 but reading in the reverse direction is positioned parallel to shaft 110 and in indicating relationship to pointer 117.

40 This described transmission mechanism will function to selectively accumulate only certain of the rotations in one direction only of main shaft 100, and these selected rotations will be accumulated in shaft 104 and their cumulative total indicated on scale 128 by pointer 124. The operation is as follows: Sufficient friction is applied to shaft 104 by means of member 132 to make shaft 104 more difficult to rotate than shaft 110. Nut 122 is initially positioned at the left hand end of shaft 104 at the zero position on scale 128, while nut 116 is at its maximum right hand position against the stop member 120, corresponding to the zero position on scale 134'. Assume main shaft 100 is rotated in the forward (clockwise) direction for fifty revolutions, nut 122 will move along shaft 104 in the right hand direction to the position 50 on scale 128. At the same time, since nut 116 is already 45 at its maximum right hand position, shaft 110 50

is locked and cannot turn, and although friction has been applied to shaft 104, it will, nevertheless, be selectively rotated by main shaft 100 through the differential 102. Now assume main shaft 100 is rotated in the reverse direction for twenty rotations. Both shafts 104 and 110 will tend to rotate in the reverse direction, but because of the friction applied to shaft 104, and the normal differential action of differential 102, only shaft 110 will be selectively rotated in the reverse direction, shaft 104 remaining stationary, and the nut 116 will move back from its zero position to the position 20 on scale 134'. Thus the indicia on the respective scales will now show that shaft 104 has turned fifty revolutions, or feet, in the forward direction while shaft 110 has moved twenty revolutions or feet in the reverse direction. If these indications are considered to represent well operations, scale 128 will correspond to a showing that the maximum depth of the well is fifty feet while scale 134' will show that the bit is at a position twenty feet "off-bottom." Now, however, it is desired to again rotate main shaft 100 in the forward direction, but is desired that no additions be made to the reading on scale 128 until nut 116 has returned to its zero position, that is, using the well drilling analogy, no increases in depth should appear until the drilling string is again on-bottom, irrespective of any intermediate movements of the drilling string. Since nut 116 is now at the 20 position, when main shaft 100 is rotated in the forward direction, both driven shafts would ordinarily tend to rotate in the same direction. However, because of the friction applied to shaft 104, shaft 110 will be preferentially rotated by main shaft 100 acting through differential 102 until nut 116 has moved forward twenty threads and comes up against stop member 120. Immediately that nut 116 comes against stop member 120, the rotations of shaft 100 will immediately be transferred by normal differential action to shaft 104 which will again begin moving nut 122 in the right hand direction from the 50 position as many threads as shaft 100 has turned, less the twenty turns necessary to bring nut 116 back to its zero position. Translating again to well drilling operations: only after the drilling string is again "on-bottom" is the maximum depth recorder released to record subsequent increases in depth.

It will also be apparent from the foregoing description, that so long as nut 116 remains away from stop 120, shaft 110 may be turned in either direction by shaft 100, and as many times as desired, without affecting the maximum attained position of nut 122. Only when the number of turns of shaft 110 in the forward direction brings nut 116 against stop 120, will shaft 104 be released to move nut 122 further in the right hand direction. Translating again to well drilling operations: So long as the drilling string remains "off-bottom" the string may engage in any number of vertical movements of any length without affecting the recording of the maximum well depth. At the same time every change in position of the string relative to the bottom of the well will be continuously recorded on the off-bottom register.

It will be apparent also that by the application of friction to shaft 104 and the described arrangement of the parts of the transmission apparatus, shaft 104 will be constrained to rotate in one direction only, the forward direc-

tion, while shaft 110 will have limited rotation in the corresponding direction and relatively unlimited rotation in the opposite direction.

Stated briefly, the novel form of selective transmission above described comprises a main shaft which is intermittently rotative in opposite directions for varying numbers of rotations, and means for accumulating selected rotations in one direction only of the main shaft. The accumulative means comprise first and second driven shaft, means constraining the first shaft to rotate in one direction only with the main shaft, a member limiting the rotation of said second driven shaft in said one direction while permitting relatively unlimited rotation thereof in the opposite direction, and means, such as a differential member, cooperating between the driven shafts whereby the first driven shaft is released for rotation with the main shaft, only when the rotation of the second driven shaft in the forward direction has been stopped by the limiting member.

A more practical form of chart drive, which, however, employs the principal features of the aforescribed selective transmission, is illustrated in Figs. 4, 5 and 6. Main shaft 42 carrying pulley 10 which receives the rotations transmitted from the measuring wheel 11 as above described, is connected through auxiliary differential 44, the details and functions of which will be described hereinafter, by means of shaft 42a to the selecting differential 46 which corresponds in function to differential 102 of the above described transmission. Shaft 42a carries a pinion 43 which is drivingly connected to ring gear 46 of the differential 46 which transmits the rotations of the main shaft through the corresponding mitre gears 47 and 49 to differential shafts 50 and 48, respectively. Shaft 50 is drivingly connected by chain drive 58 to counter-shaft 60 corresponding to driven shaft 104 above. Shaft 60 drives maximum counter 62 and stub shaft 64. A pinion 51 mounted on stub shaft 64 turns a gear 53 which in turn drives a shaft 55 carrying a worm 57 which engages a gear 59 which is mounted on a shaft 61 for turning the driving roll 63 for strip chart 40, and for unwinding it from feed roll 65. The gear ratios carried through the transmission apparatus to the chart are preferably such that the chart is moved in the direction of the adjacent arrow through intervals corresponding to one rotation of main shaft 42 which in turn represents one foot of vertical movement of the drilling string, as above explained. The chart 40 is preferably marked with lines spaced at intervals of one-fiftieth of an inch. That is, one inch of movement of the chart represents 50 feet of depth of the well, and each rotation of main shaft 42 will move the chart one-fiftieth of an inch. Numeral 67 designates a representation of a conventional form of marking pen which traces on chart 40 the record of any test made by any suitable instrument, not shown, of the character of the formation or the drilling conditions in the well at the particular depths shown at the left hand side of the chart.

Shaft 60 carries a brake drum 69 against which is pressed a brake block 71 constructed of any suitable friction material. These elements correspond to the friction applying member 132, above described. The details of the brake mechanism are shown in detail in Fig. 5 and consist of a curved arm 73 which is pivotally attached by one end at 75 to some convenient portion of the

transmission frame, not shown. Brake block 71 surrounds the intermediate portion of arm 73 and is held in engagement with the surface of drum 69 by connecting the free end of arm 73 to a coil spring 77 which is in turn connected to a convenient portion of the transmission frame, not shown. The tension of spring 77 is adjusted so that the proper amount of friction can be applied through drum 69 to shaft 60. Counter 62 may be any one of the conventional types of revolution counters, such as, for example, the commercial form of counter known as the "Productimeter," manufactured by the Durant Mfg. Company of Milwaukee, Wisconsin as its model 5-BA-711-C counter, and corresponds in function to scale 128 and pointer 124, above.

Returning now to differential shaft 48. This shaft is connected by a sprocket and chain drive 52 to countershaft 54 which drives counter 56, referred to as the "off-bottom" counter, equivalent to scale 134' and pointer 117, above. This counter is similar in construction to counter 62 except that it is provided with stop mechanism which, while permitting rotation of the indicia wheels in either direction when the number of revolutions recorded thereon is greater than zero, prevents any rotation of the indicia wheels from the zero position in the opposite direction toward the 9-9-9 position. That is, the indicia wheels are free to move forwardly from the zero position to any position up to that representing the maximum recording capacity of the counter shown, namely, 999, and in the reverse direction between this maximum and the zero position, but cannot move in the opposite direction from the zero position. This stop mechanism corresponds to stop member 120, of the above described simplified transmission, and consists of a lug 79 which is affixed to the zero marking on the left hand indicia wheel 83 and extends radially therefrom. Lug 79 cooperates with a second lug 81 mounted inside the counter case and extending toward indicia wheel 83 and under lug 79 (Fig. 6). Thus while indicia wheel 83 is free to rotate counter-clockwise from lug 81, that is in the forward direction to the maximum counting capacity of the counter, namely 999 revolutions, and in the opposite direction to any position corresponding to any number of rotations greater than zero, it can never move past the counter's zero position, and the rotation of shaft 54 is thus locked against rotation beyond this position.

The manner in which the selective transmission just described functions to drive the chart 40 from the movements of the drilling string will now be described.

For purposes of this illustrative description, reference being had particularly to Figs. 1, 4, 5 and 6, we will assume that drilling operations are about to begin, bit 30 being at the top of the ground. In accordance with conventional practice, all depth measurements are made from the upper face of the rotary table as the zero point. The space between the top of the ground and the top of the rotary table is normally of sufficient depth to receive the bit and drill collar when attached to the lower end of the kelly. Both counters 56 and 62 will be at their respective zero positions. The wheels of "off-bottom" counter 56 will be locked in this position by the described cooperation of lugs 79 and 81, since this counter is designed to turn in the opposite direction to counter 62 in measuring distances "off-bottom." Drilling is now begun. As the drilling string 20 moves downwardly in the well,

traveling block 16 moves correspondingly downward, rotating crown block pulley 14 in a direction corresponding to such movement, and drives measuring wheel 11 which in turn transmits its rotations, representing the footage of downward movement, to main shaft 42 of the selective mechanism. The corresponding forward rotation of main shaft 42 is transmitted through differentials 44 and 46 to maximum counter 62, which registers the progressively increasing depth of the well, and at the same time drives chart 40 which has also been started from its zero position when drilling began. The depth reading on chart 40 will correspond to the depth reading appearing on counter 62, the chart moving an interval corresponding to one foot of depth for each rotation of shaft 60 and for each increase of one digit in the reading on counter 62. These movements continue until the drilling has proceeded for an interval substantially equal to the length of the kelly 26, say 40 feet. However, since measurement is normally begun when the lower end of the drill bit begins to descend below the level of the top of the rotary table, the total measurement recorded after the full length of the kelly has been drilled will be 40 feet, the length of the kelly, plus the length of the bit stem and collar, which is, say, 20 feet, or a total length of 60 feet will be recorded. Counter 62 and chart 40 will each record 60 feet as the maximum depth of the well. Counter 56 will, of course, continue to show a zero reading since it is locked in this position as above described. It now becomes necessary to add another joint of drill pipe, say 40 feet in length, in order to continue deepening the well. To perform this operation, the drilling string must be drawn upwardly out of the well until the lower end of the kelly is above the rotary table 32. This requires that the bit be lifted off the bottom a distance somewhat greater than the length of the kelly so that the upper end of drill collar and bit may be grasped by the usual slips and held so that the kelly may be unscrewed. Assume that this reverse movement is 50 feet. Traveling block 16 will of course move upward a similar distance and produces corresponding reverse rotations of crown block pulley 14, which will be immediately transmitted to the selective transmission in the form of reverse rotations of main shaft 42 which are in turn transmitted to countershafts 54 and 60. However, since friction has been applied to shaft 60 through the medium of brake 68, and since shaft 54 is free to rotate in the reverse direction, differential 46 will become operative through the friction in shaft 60 to selectively rotate shaft 54 in the reverse direction while shaft 60 remains stationary. Shaft 54 will, therefore, rotate the wheels of counter 56 in accordance with the reverse rotations of main shaft 42 until the counter wheels register 50 feet, the distance through which the traveling block and the drilling string have moved upwardly in the well. The reading on counter 56 of 50 feet is the present "off-bottom" position of the bit, while counter 62 and chart 40 continue to record the maximum depth as 60 feet.

In order to add the new joint of drill pipe, the kelly must be unscrewed from the bit stem and set to one side while the traveling block and hook are employed to hook on to the new section of pipe, and lift it in place to be screwed to the bit stem. All of these auxiliary movements of the traveling block are, of course, transmitted to the crown block pulley 14 and thence to the transmission mechanism whereby they produce corre-

sponding changes in the readings of counter 56, since all of these changes occur while the bit is "off-bottom." All of these auxiliary movements of traveling block 16 have, of course, no significance with regard to the maximum depth of the well, or to the actual off-bottom position of the bit, since these remain unchanged. When, however, the new joint of drill pipe which is 40 feet in length, is in place on top of drill string extending above the floor of the derrick, traveling block 16 will necessarily have returned to the same position it had previously attained when it lifted the drilling string and kelly out of the well, namely 50 feet off-bottom, and counter 56 will accordingly again carry a reading of 50 feet. Now it is necessary to replace the kelly at the top of the drilling string and in order to do this, the traveling block must lower the drilling string, now including the new joint of pipe, into the well until only the upper end protrudes above the rotary table. Assume this downward movement to be 40 feet. The reading of counter 56 will thereupon be reduced by the corresponding downward movement of the traveling block and will now read 10 feet, the present distance off-bottom of the bit. Traveling block 16 is now disconnected from the upper end of the drill pipe and connected to the kelly which is swung into place and screwed to the upper end of the drilling string. When this operation has been completed, traveling block 16 will have come to rest again, at an upward position in the derrick above the upper end of the added joint of drill pipe equal to the length of the kelly, namely 40 feet, and this additional upward movement will have been recorded on counter 56, which will now register an off-bottom measurement of 50 feet, although, as noted, the actual position of the bit will have remained unchanged at 10 feet off-bottom. Now, as the entire drilling string is lowered in the well to bring the bit on-bottom, traveling block 16 will move downwardly only 10 feet to attain the on-bottom position, and the corresponding recording on counter 56 will bring its reading down from 50 feet to 40 feet. If now, drilling would be permitted to proceed, no additional footage, representing the deepening of the well, would be recorded on maximum counter 62, since counter 56 had not yet reached its zero position so as to release countershaft 60 to turn counter 62. It is necessary, therefore, to provide some means for returning the reading of counter 56 to zero when the bit has actually touched bottom, so that shaft 60 may be released and immediately begin recording on counter 62 the further downward movement of the bit from the previously attained maximum depth. In performing this operation of returning counter 56 to its zero reading, what is actually done, is to subtract from the reading of counter 56 the footage representing the length of the new joint of drill pipe which has been added to the drilling string. This operation is performed by means of auxiliary differential 44 which has been previously adverted to, and its construction and function will now be described in detail.

As illustrated particularly in Fig. 4, auxiliary differential 44 is of more or less conventional construction and is arranged between main drive shaft 42 and selecting differential 46 so that shaft 42 drives directly through the mitre gears 87 of differential 44 to differential 46 without variation in the movements imparted to differential 46 except possibly to reverse the direction of rotation of shaft 42a which connects the two differen-

tials. This reversal of rotation is, of course, again corrected by the various gear and drive connections in differential 46 so that the rotations of the driven shafts 48 and 50 correspond in the desired manner to the vertical movements of the drilling string. The spider 89 of the differential 44 carries a conventional ring gear 91 which is in mesh with a pinion 93 carried on the end of a shaft 95 to which is attached a handle 97. During the transmission through differentials 44 and 46 of those rotations of main shaft 42 which represent vertical movements of the drilling string, ring gear 91 remains stationary. When, however, it is desired to subtract the additional footage represented by the added joint of drill pipe, the handle 97 is turned, rotating ring gear 91 which in turn rotates countershaft 54, as this shaft is still free to turn toward the zero position, since its reading is 40 feet, although the bit is actually on bottom. As many rotations are thus made as are necessary to equal the footage of the added section of drill pipe. Since, as noted, this added section was 40 feet long, when the number of turns of auxiliary differential 44 equivalent to this footage has been made, 40 feet will have been subtracted from the reading of counter 56 and its reading will become zero, which is the true reading, since the bit is on bottom. Now when drilling is again begun, causing corresponding downward movement of the traveling block 16, this movement will be transferred through differential 46 to shaft 60 because counter 56 has now become locked at its zero position and counter 62 and chart 40 will accordingly begin registering the increasing depth.

The aforescribed operations, including the corrective rotations of auxiliary differential 44 are repeated for each addition of sections to the drilling string, and it will be apparent that countershaft 60 will accumulate only those downward movements of traveling block 16 which represent progressively downward movements of the bit. These accumulated movements will be registered on maximum counter 62 and on chart 40 which will be moved in exact accordance therewith. It will also be evident that off-bottom counter 56 by its construction provides means, acting through the medium of differential 46 and friction brake 68 to selectively transmit to counter 62 and chart 40 only those movements of main shaft 42 which correspond to progressively downward movements of the drill bit.

It will be understood that auxiliary differential 44 may be employed either for adding or subtracting corrective rotations to the shafts 54 and 60, depending upon whether sections of drill pipe are being added to, or removed from, the drilling string, or to correct for errors in the length of the drilling string. By the form of its construction and its arrangement auxiliary differential can be employed to introduce rotations into the transmission mechanism while main shaft 42 is rotating or stationary, and the rotations thus introduced will correspondingly alter the reading of counters 56 and 62 independently of the number of rotations already made by main shaft 42.

Fig. 7 illustrates a modified form of off-bottom counter 56 which, by its construction, combines in a single piece of equipment, the functions of the off-bottom counter and of the auxiliary differential 44. In this modified form, the ends of shaft 54 which extend beyond each end of the case 109 of the counter, which will be designated 98, are journalled in bearings 99 and 101 which are

carried on uprights 103 and 105, respectively, which are supported on a base member 107 extending beneath counter 98. Mounted on the right hand end of shaft 54 and fixedly attached to the case 109 of counter 98 is a bevel gear 111 which is in mesh with a pinion 113 carried by a shaft 115 which extends through base member 107 and is journaled therein. The free end of shaft 115 carries a handle 119. Counter 98 functions normally in exactly the same manner as counter 56 in the earlier described modification. However, when corrections in the reading of counter 98 are to be made to account for the adding-in of sections of drill pipe to the drilling string, by turning handle 119 in the proper direction, the case 109 of the counter will be rotated and will change the reading of the counter in accordance with the number of turns made. The turning of the case will effect the same subtraction in the counter as is effected by the operation of auxiliary differential 44, as previously described. It will be understood that various other forms of apparatus may be similarly designed for use with the transmission mechanism of this invention to introduce the corrections occasioned by the additions to the length of the drilling string.

The aforescribed chart drive system may be employed as described to effect a selection from all of the movements of traveling block 16 of only those particular movements which are to be employed to drive the chart, or particular movements of the drilling tools which are coupled to the chart drive may be pre-selected, as by means of the apparatus shown in my former Patent No. 2,166,212, or in my co-pending application Serial No. 279,422, filed June 16, 1939, now U. S. Patent No. 2,221,767, Nov. 19, 1940, or by any other suitable means.

The transmission mechanism of this invention, and particularly shaft 60, since it is controlled to rotate in exact synchronism only with the progressive downward movements of the drill, may be very usefully employed to drive mechanism other than the chart, where it is desired to operate such other mechanism in synchronism with the downward movement of the drill. Accordingly, a gear 130 is mounted on stub shaft 64 and is arranged to mesh with a gear 132 carried by an auxiliary shaft 134 which may be employed to drive such other mechanism in accordance with the downward movement of the drill. This auxiliary drive is particularly useful for driving mechanism such as drilling rate indicators, generally illustrated at 154 in Fig. 8, which is illustrated as driving marking pen 67 to trace the record of drilling rate against depth on chart 40.

Figs. 8, 9, 10 and 11 illustrate a modified form of the chart drive of this invention. In this modified form, the stop member in counter 56, which normally functions as a control for the movements of shaft 60 and counter 62, includes an electrical switching arrangement which is employed to automatically control and perform a number of useful operations. Primarily it is employed to automatically control the movements of shaft 60, by actuating an electric control for brake 68, which automatically releases brake 68 and allows shaft 60 to rotate forwardly when the indica wheels of counter 56 attempt to move beyond the zero position, and automatically sets brake 68 when the reading of counter 56 is greater than zero, irrespective of the direction of rotation of shaft 54. Other useful functions of

the switching arrangement will be described hereinafter in connection with the detailed description of this new modification.

Referring to Figs. 8 to 11, a normally open switch consisting of a detent arm 134 and a fixed arm 136 are mounted inside the case of counter 56 and detent arm 134 is arranged so as to be depressed into contact with fixed arm 136 by pressure from lug 79 when indica wheel 83 attempts to move past its zero position toward the 9-9-9 position of the counters. Wire leads 133 and 135 connect arms 134 and 136, respectively, in circuit with a group of relays 137, 138 and 139, and with a suitable current source such as a battery 140. The relays control switches 141, 142 and 143, respectively. Relay switch 141 is connected by leads 144 and 145 in circuit with a battery 146 and with a solenoid 147 which controls the operation of brake 68. Brake 68 has been slightly redesigned for adaption to electrical control, as illustrated in detail in Fig. 9. Brake drum 69 is provided with a ratchet wheel 148 which is fixedly attached parallel to drum 69 and cooperates with a pawl 149 which is hingedly attached to the case of counter 62. The pawl 149 cooperates with ratchet wheel 148 so as to positively prevent reverse rotation of shaft 60. That is, shaft 60 can now move only in the forward direction representing progressive downward movement of the drill. The free end of brake arm 73 is pivotally attached to the end of the armature 150 of solenoid 147, and an extension of armature 150 is connected to an end of coil spring 77 which is now arranged to normally hold arm 73 and brake block 71 out of engagement with brake drum 69.

The electric control of brake 68 operates as follows: When the drill bit is on bottom, counter 56 will register zero on all its wheels, as previously described. At the instant further drilling begins, countershaft 54 will tend to rotate beyond the zero position and the initial rotary movement will cause lug 79 to depress arm 134 and close the counter switch which will in turn immediately open relay switch 141 cutting off the flow of current in the windings of solenoid 147. Armature 150 will thereupon be released and will be pulled upwardly by the tension of spring 77 and will draw brake block 71 out of braking engagement with brake drum 69, and releases shaft 60 for rotation. As long as the drill continues to move downwardly in the well, shaft 60 will remain free to rotate the wheels of counter 62 and the drive to chart 40 in accordance with the downward movement of the bit. When, however, the bit is lifted off-bottom the corresponding reverse movement of the wheels of counter 56 will relieve the pressure of lug 79 on detent arm 134 and break its contact with arm 136. This action will in turn cause relay switch 141 to close actuating solenoid 147 to draw armature 150 down and thereby pull brake block 71 into braking engagement with drum 69 thus effectively stopping any reverse movement of countershaft 60. However, since the initial reverse movement of the bit would normally tend to cause corresponding reverse movement of shaft 60, as well as of shaft 54, since the brake on shaft 60 is not yet engaged, then, in order to prevent any such reversal of shaft 60, and to permit preferential reversal of shaft 54 so as to cause the switch in counter 56 to actuate and set the brake on shaft 60, ratchet 148 and pawl 149 are provided to cooperate to prevent any reverse movement of shaft 60, and thus enforce the desired preferential rotation of shaft 54 which results in setting of the

brake 68. When the brake 68 has thus become set, no movements of the traveling block 16 occurring while the bit is off-bottom can affect counter 62 until such movements occur as will bring counter 56 back to the zero position so as to again close the circuit to relay 137 and release brake 68.

Relay 138 is employed to operate a lamp 151 and bell 152 which are arranged in parallel in circuit with switch 142. Relay switch 142 is arranged to close this circuit when the switch formed by arms 134 and 136 is closed. That is, when the bit is on bottom. Closing of switch 142 lights up lamp 151 and rings bell 152, thus giving the drill operator both a visible and an audible signal when the bit is on bottom. The lamp 151 is ordinarily allowed to remain lighted as long as the bit is on bottom or drilling ahead. Bell 152 may be cut-off by means of a switch 153 after it has given warning that the bit has touched bottom.

Switch 143 is also arranged to close when the switch in counter 56 closes, and is connected in circuit with an instrument such as a conventional drilling rate indicator 154 which is shown as operating pen 67. The circuit connects relay switch 143 with a conventional pen control mechanism in indicator 154, so that when drilling is proceeding the pen traces its record on chart 40 in relation to the progress of the drill. When, however, drilling stops, and the bit lifted off-bottom, chart 40 likewise stops in accordance with the previously described operation of the chart drive. At the same time, obviously, it becomes desirable to stop the tracing movement of the pen 67 since any trace made by it while no drilling took place is clearly meaningless. Accordingly, opening of the switch in counter 56 when reverse movements of the drilling tools occur, opens relay switch 143 and stops pen 67 at exactly the point it occupied at the instant chart 40 has likewise stopped.

It will be seen, therefore, that the switch in counter 56, in addition to aiding in the automatic selection of the movements of the drilling tools to be transmitted to chart drive 40, may be employed for numerous other functions related to the position of the drill in the well. In addition to those specifically enumerated above, the switch may be employed, through the use of additional relays, in other capacities and for other uses which will be apparent to those skilled in the art to which this invention appertains.

It will be apparent that numerous modifications and alterations may be made in the details of construction and in the form of arrangement of the parts of this invention without departing from the scope of the appended claims.

What I claim and desire to secure by Letters Patent is:

1. In combination with a drilling string and a well depth exhibiting means adapted to exhibit the depth of the well in accordance with the downward progress of said drilling string in the well, a drive for said exhibiting means, comprising, a main drive shaft driven from said drilling string and reversibly rotative in synchronism with corresponding measured vertical movements of said drilling string, a first driven shaft drivingly connecting said main drive shaft to said exhibiting means, a second driven shaft driven by said main drive shaft, a differential member connecting said main shaft to said first and second driven shafts, means operative upon said first driven shaft to constrain its rotation

with the main shaft in one direction only corresponding to downward progress of said drilling string in the well and to render said second driven shaft normally preferentially rotatable by said main shaft, and means cooperating with said second driven shaft to limit its rotation with the main shaft in said one direction while permitting relatively unlimited rotation thereof in the opposite direction.

2. In combination with a drilling string and a well depth exhibiting means adapted to exhibit the depth of the well in accordance with the downward progress of said drilling string in the well, a drive for said exhibiting means comprising, a main drive shaft driven from said drilling string and reversibly rotative in synchronism with corresponding measured vertical movements of said drilling string, a first driven shaft drivingly connecting said main drive shaft to said exhibiting means, a second driven shaft driven by said main drive shaft, a differential member connecting said main drive shaft to said first and second driven shafts, means operative upon said first driven shaft to constrain its rotation with the main shaft in one direction only corresponding to downward progress of said drilling string in the well and to render said second driven shaft normally preferentially rotatable by said main shaft, and a revolution counter reversibly driven by said second driven shaft and including means for preventing rotation of said second driven shaft in said one direction when said counter attains its zero reading in that direction.
3. In combination with a drilling string and a well depth exhibiting means adapted to exhibit the depth of the well in accordance with the downward progress of said drilling string in the well, a drive for said exhibiting means comprising, a main drive shaft driven from said drilling string and reversibly rotative in synchronism with corresponding measured vertical movements of said drilling string, a first driven shaft drivingly connecting said main drive shaft to said exhibiting means, a second driven shaft driven by said main shaft, and means cooperating between said first and second driven shafts and said main drive shaft whereby said first driven shaft is constrained to drive said exhibiting means in one direction only corresponding to progressive deepening movements of said drilling tools in the well, and auxiliary means for rotating said driven shafts independently of said main drive shaft.
4. In combination with a drilling string and a well depth exhibiting means adapted to exhibit the depth of the well in accordance with the downward progress of said drilling string in the well, a drive for said exhibiting means comprising, a main drive shaft driven from said drilling string and reversibly rotative in synchronism with corresponding measured vertical movements of said drilling string, a first driven shaft drivingly connecting said main drive shaft to said exhibiting means, a second driven shaft driven by said main shaft; and shaft selecting means cooperating between said first and second driven shafts and said main drive shaft whereby said first driven shaft is selectively constrained to drive said exhibiting means in the direction only corresponding to progressive depending movements of said drilling tools in the well and auxiliary means for altering the accumulated rotations of said driven shafts independently of said main drive shaft.

5. In combination with a drilling string and a well depth exhibiting means adapted to exhibit the depth of the well in accordance with the downward progress of said drilling string in the well, a drive for said exhibiting means comprising, a main drive shaft driven from said drilling string and reversibly rotative in synchronism with corresponding measured vertical movements of said drilling string, a first driven shaft drivingly connecting said main drive shaft to said exhibiting means, a second driven shaft driven by said main drive shaft, a differential member connecting said main shaft to said first and second driven shafts, means operative upon said first driven shaft to constrain its rotation with the main shaft in one direction only corresponding to downward progress of said drilling string in the well and to render said second driven shaft normally preferentially rotatable by said main shaft, and means cooperating with said second driven shaft, to limit its rotation with the main shaft in said one direction while permitting relatively unlimited rotation thereof in the opposite direction, and an auxiliary differential member cooperating with said first and second driven shafts for altering the accumulated rotations thereof independently of said main drive shaft.

6. In combination with a drilling string and a well depth recording chart adapted to record the depth of the well in accordance with the downward progress of said drilling string in the well, a drive for said chart comprising, a main drive shaft driven from said drilling string and reversibly rotative in synchronism with corresponding measured vertical movements of said drilling string, a first driven shaft drivingly connecting said main drive shaft to said chart, said first driven shaft being releasably constrained to rotate with said main shaft in one direction only corresponding to said downward movements of said drilling string, a second driven shaft reversibly driven by said main shaft, means limiting the rotation of said second driven shaft in said one direction while permitting relatively unlimited rotation thereof in the opposite direction, and means cooperating between said first and second driven shafts whereby the former is released for rotation with the main drive shaft in said one direction only upon the attainment by said second driven shaft of the limit of its rotation in said one direction.

7. In combination with a drilling string and a well depth exhibiting means adapted to exhibit the well depth in accordance with the downward progress of said drilling string in the well, a drive for said exhibiting means comprising, a main drive shaft driven from said drilling string and reversibly rotative in synchronism with corresponding measured vertical movements of said drilling string, a first driven shaft drivingly connecting said main drive shaft to said exhibiting means, a second driven shaft driven by said main drive shaft, a differential member connecting said main shaft to said first and second driven shafts, means constraining said first driven shaft to rotate with said main drive shaft in one direction only corresponding to downward progress of said drilling string in the well, releasable brake means cooperating with said first driven shaft to render said second driven shaft preferentially rotatable in said one direction by said main drive shaft, stop means cooperating with said second driven shaft to limit its rotations with the main shaft in said one direction while permitting relatively unlimited rotation thereof in the opposite direc-

tion, and means associated with said stop means and operative upon the limitation of rotation of said second driven shaft thereby to release said brake.

5 8. Apparatus according to claim 7 including, an electrically controlled release means for said brake, and an electrical switch means in circuit therewith and actuatable by said stop means to release said brake.

10 9. Apparatus for recording well depths during drilling comprising, a drilling string movable vertically in a well, a traveling block for suspending the drilling string and movable vertically in concert therewith, a pulley from which the traveling block is suspended and which is rotative by the traveling block in accordance with its vertical movements, a measuring wheel driven by said pulley for measuring the vertical movements of the traveling block, a selective transmission driven by said measuring wheel in synchronism with the measured vertical movements of said traveling block, a depth recording chart releasably driven by said selective transmission, said selective transmission including selecting means arranged to be operative only by those measured vertical movements of the traveling block corresponding to progressive deepening of the well to drivingly connect said mechanism to said chart, well logging apparatus for placing well logging data on said chart, and control means operative by said selecting means in said transmission mechanism for causing said logging apparatus to place its record on said chart only when said chart is being driven by said mechanism.

30 10. In combination with a drilling string movable vertically in a well, a strip recorder chart bearing footage indicia representative of the depth of said well and adapted to be driven in synchronism with the downward progress of said drilling string in the well, apparatus for placing continuous records of drilling operations on said chart, and a chart drive, comprising, a selective transmission mechanism releasably connecting said drilling string to said chart, said transmission mechanism including selecting means arranged to be operative only by those downward movements of the drilling string which constitute progressive deepening of the well to drivingly connect said mechanism to said chart, and control means operative by said selecting means to thereby cause said records to be placed on said chart by the recording apparatus only when said chart is being driven by said mechanism.

35 11. In combination with a drilling string and a well depth register adapted to register the depth of a well in accordance with the downward progress of the drilling string therein, a drive for said register comprising, a main drive shaft driven from the drilling string, a differential connected to said main drive shaft, first and second revolution counters driven by said main drive shaft through said differential, means constraining said first counter to cumulatively count revolutions of the main drive shaft in one direction only corresponding to downward progress of said drilling string, retarding means operative upon said first counter whereby said second counter is reversibly driven by the main shaft normally preferentially relative to said first counter, and means to lock said second counter against rotation in said one direction upon attainment of its zero reading in that direction to thereby cause further rotations of said main shaft in that direction to preferentially drive said first counter.

70 75 12. In combination with a drilling string

adapted to move vertically in a well and a well depth recording chart adapted to be driven in accordance with the downward progress of the drilling string in the well, a drive for said chart comprising, a main drive shaft driven from the drilling string, a differential driven from said shaft and having one branch drivingly connected to said chart, means constraining the chart to move in one direction only corresponding to downward progress of said drilling string, a revolution counter connected to said main shaft through a second branch of said differential and reversibly driven thereby normally preferentially relative to said chart, and means to lock said revolution counter against rotation in said one direction upon attainment of its zero reading in that direction to thereby cause further rotations of said first branch in that direction to preferentially drive said chart.

13. In combination with a drilling string and a well depth exhibiting means adapted to exhibit the depth of the well in accordance with the downward progress of the drilling string in deepening the well, a drive for said exhibiting means, comprising, a main drive shaft driven from said drilling string and reversibly rotative in synchronism with corresponding measured vertical movements of said drilling string, a first driven shaft drivingly connecting said main drive shaft to said exhibiting means and constrained to rotate in one direction only corresponding to downward movements of said drilling string, a second driven shaft reversibly driven by said main shaft normally preferentially relative to said first driven shaft, and means actuatable by pre-determined limitation of the rotation of said second shaft in said one direction to produce preferential rotation of said first driven shaft in said direction.

14. Apparatus for recording well depths during drilling, comprising, a drilling string adapted to move vertically in a well, a well depth recorder, a drive for said recorder, said drive comprising, a main drive shaft driven from the vertical movements of said drilling string, a differential driven

from said shaft and having a first branch drivingly connected to said recorder, means constraining said recorder to move in one direction only corresponding to downward progress of said drilling string, a second branch of said differential reversibly driven by said main shaft normally preferentially relative to said recorder, and means to lock said second branch against rotation in said one direction upon attainment of a pre-determined limit of rotation in that direction to thereby cause further rotations of said first branch in that direction to preferentially drive said recorder.

15. In combination with a drilling string and a well depth register adapted to register the depth of a well in accordance with the downward progress of the drilling string therein, a drive for said register, comprising, a main drive shaft driven from the vertical movements of said drilling string, a differential member connected to said main drive shaft, first and second revolution counters driven by said main drive shaft through said differential member, said second counter being reversibly driven by the main drive shaft normally preferentially relative to said first counter, and means to lock said second counter against rotation in one direction upon attainment of its zero reading in that direction to thereby cause further rotations of said main shaft in that direction to preferentially drive said first counter in that direction.

16. Apparatus for recording well depths during drilling comprising in combination with a drilling string movable vertically in a well, a well depth recording means, a transmission mechanism operative only by those downward movements of the drilling string which correspond to progressive deepening of the well to drivingly connect said drilling string to said recording means, and an auxiliary adjusting mechanism for altering the position of said transmission mechanism to compensate for changes in length of said drilling string.

JOHN T. HAYWARD.
